ABSTRACT OF THE DISCLOSURE

Esters of lysergic and dihydrolysergic acids, including 4-alkyl, 4-alkenyl and 4-aralkyl derivatives thereof, in which the esterifying group is derived from a dihydroxy or trihydroxy alkyl alcohol having from two to eight carbon atoms or a C₅ to C₁₁ cycloalkyl dihydroxy alcohol, having from 5 to 8 ring carbon atoms, the esters having neurosedative activity in animals.

BACKGROUND OF THE INVENTION

Extensive research in the field of mental health has uncovered a variety of therapeutic agents useful in the treatment of various mental conditions. The commonly used tranquilizers, psychic energizers, antidepressants and neurosedatives of today are a result of this research. Although significant advances have been made by the development of compounds having these activities, there remains the need for more effective agents.

This invention comprises novel compounds which possess desirable neurosedative properties.

SUMMARY OF THE INVENTION

This invention relates to novel esters of certain indoloquinoline carboxylates. More particularly, this invention relates to polyhydric alcohol esters of lysergic and dihydrolysergic acids wherein the polyhydric alcohol is alkyl and has from two to eight carbon atoms or is a C₅ to C₁₁ cycloalkyl having from five to eight ring carbon atoms.

DETAILED DESCRIPTION

The novel esters of this invention have the following structural formula wherein the numbering of the indoloquinoline ring system is indicated:

and wherein the 10, 10a-bond may be unsaturated, as shown, or saturated. In the above formula, R¹ is hydro-

2

gen, methyl, ethyl, propyl, isopropyl, allyl or benzyl and R² is the residue of an alkyl polyhydric alcohol having from two to eight carbon atoms or a C₅ to C₁₁ cycloalkyl polyhydric alcohol having from five to eight ring carbon atoms. Also a part of the present invention are the salts of the compounds of the above formula.

As employed herein, the term "polyhydric alcohol" refers to a dihydroxy or trihydroxy alcohol. Illustrative of such alcohols which can be employed in the preparation of the esters of this invention are

- ethylene glycol,
- propane-1,2-diol,
- propane-1,3-diol,
- glycerol,
- 15 2,2-diethylpropane-1,3-diol,
- 2-ethyl-2-methylpropane-1,3-diol,
- butane-1,4-diol,
- 2-methylbutane-1,4-diol,
- butyne-1,4-diol,
- 20 butane-1,3-diol,
- butane-2,3-diol,
- butane-1,2,4-triol,
- pentane-1,5-diol,
- pentane-1,4-diol,
- 25 2-methylpentane-2,4-diol,
- hexane-1,6-diol,
- hexane-2,5-diol,
- 2,5-dimethylhexane-2,5-diol,
- heptane-1,7-diol,
- 30 octane-1,8-diol and the like.

Illustrative of the cycloalkyl polyhydric alcohols which can be employed in the present invention are

- 35 cyclopentane-1,3-diol,
- cyclohexane-1,4-diol,
- 5,5-dimethylcyclohexane-1,3-diol,
- 2-ethylcyclopentane-1,3-diol,
- cycloheptane-1,2-diol,
- 40 4-methylcycloheptane-1,2-diol,
- cyclooctane-1,5-diol,
- 3-ethylcyclooctane-1,3-diol,
- 4-isopropylcycloheptane-1,2-diol,
- 3-propylcyclooctane-1,5-diol,
- 45 3-isopropylcyclooctane-1,5-diol and the like.

The polyhydric alcohols which can be employed in the preparation of the novel esters of this invention are available from commercial sources or they can be obtained by commonly known synthetic methods.

- 50 The compounds of the present invention are formally named as esters of 7-methyl-4,6,6a,7,8,9-hexahydroindolo[4,3-fg]-quinoline-9-carboxylates and of 7-methyl-4,6,6a,7,8,9,10,10a-octahydroindolo[4,3-fg]-quinoline - 9 - carboxylates. Informally, the compounds are designated as esters of lysergic acids or dihydrolysergic acids respectively.

The novel compounds disclosed herein can all be prepared from lysergic acid by procedures known in the art. As is illustrated by the following reaction sequence, wherein R¹ and R² have the previously assigned mean-

ings, the compounds can be prepared by several alternative routes:

A=alkylation

A=alkylation
E=esterification

H₂=hydrogenation

$R^1=C_1-C_3$ lower alkyl, allyl or benzyl

R^2 =mono or dihydroxy C_1-C_8 alkyl and monohydroxy

C₅–C₈ cycloalkyl

Dashed arrows=alternate routes

Solid arrows=preferred routes

It is readily apparent from

It is readily apparent from the foregoing scheme that considerable choice is permitted with respect to the sequence in which the various process steps are carried out. This choice in reaction sequence is indicated in Flow Sheet I by means of solid and dashed arrows. Thus, for example, in the preparation of the esters of a 4-substituted lysergic acid, the esterification reaction can be performed either prior to or after the introduction of the substituent in the 4-position. Similarly, in the synthesis of the dihydrolysergic acid esters the introduction of the 4-substituent, the hydrogenation step and the esterification can be carried out in any sequence. When however, the desired 4-substituent of the dihydrolysergic acid is unsaturated, as for example, 4-allyldihydrolysergic acid, the hydrogenation step is carried out on lysergic acid or a saturated ester thereof prior to alkylation in order to avoid hydrogenation of the desired 4-substituent. Likewise, when the desired ester function of the dihydrolysergic acid is unsaturated, for example, 4-hydroxy-2-butynyl dihydrolysergic acid carboxylate, hydrogenation is carried out prior to the esterification step.

Generally speaking it is preferred to carry out the esterification procedure as the final step of the reaction sequence in either the lysergic or dihydrolysergic acid series. The esterification is conveniently effected by adding the lysergic or dihydrolysergic acid to the desired polyhydric alcohol in the presence of a suitable acid at a temperature between about 0 and 75° C. The reaction mixture is stirred vigorously until solution is obtained and the product recovered by treating the reaction product mixture with three to four volumes of water containing an excess of base and extracting with a suitable water-immiscible solvent such as ethylene dichloride, chloroform, ether and

the like. The polyhydric alcohol is desirably used in large excess and thus provides as well as suitable reaction

35 medium. When the polyhydric alcohol employed for esterification has a melting point above about 25° C. the warm melt of the alcohol can be used with success.

Among the acids which can be suitably employed in the esterification reaction are concentrated sulfuric acid and the alkyl and arylsulfonic acids such as benzenesulfonic acid, p-toluenesulfonic acid, p-chlorobenzenesulfonic acid, p-nitrobenzenesulfonic acid, methanesulfonic acid, ethanesulfonic acid and the like. The preferred acids are concentrated sulfuric acid and p-toluenesulfonic acid, although satisfactory yields of product can be obtained with the other acids listed. For best results when concentrated sulfuric acid is employed, it is preferable to carry out the esterification at a temperature between about 0 and 35° C., although significant yields of product can be obtained at higher temperatures. Small amounts of concentrated sulfuric acid suffice. For example, a convenient ratio of concentrated sulfuric acid to polyhydric alcohol is 5 ml. to 100 ml. and a convenient ratio of concentrated sulfuric acid to the lysergic or dihydrolysergic acid employed is about 1 ml. to 1 gram or less.

55 about 1 ml. of 1 gram of 4-
The 4-substituted dihydrolysergic acids employed for
esterification are conveniently prepared by the alkylation
of dihydrolysergic acid in liquid ammonia in the presence
of sodium amide according to the procedure described in
60 U.S. Pat. No. 3,183,234. The 4-substituted lysergic acids
are prepared by a procedure analogous to that employed
in the dihydro series. Thus, for example, 4-methyllysergic
acid is prepared by first forming sodium amide in liquid
ammonia, adding lysergic acid thereto, and alkylating
65 the sodio derivative of the lysergic acid so obtained with
methyl iodide or methyl sulfate.

Those skilled in the art will recognize that when the polyhydric alcohol employed in the esterification is unsymmetrically substituted, it is probable that diastereoisomers are obtained, the number of such diastereoisomeric pairs being dependent upon the number of asymmetric carbon atoms present in the alcohol. Moreover, esterification can occur with any of the available hydroxy groups of the polyhydric alcohol, so that the possibility of forming position isomers also exists. In general, it can be said

that in such cases the resulting product is a mixture of the various possible isomers.

If desired, salts of the novel esters of the invention can be prepared with physiologically acceptable acids by procedures well known in the art. Such acids may be either inorganic or organic and may include, among the latter such acids as maleic, fumaric, benzoic, p-toluenesulfonic, salicylic, mandelic, cinnamic, naphthoic, ascorbic, succinic, citric, tartaric, malic, pimelic and like acids. In general, the salts with polycarboxylic organic acids are more readily obtained in crystalline form and are, therefore, preferred. An especially preferred acid is maleic acid.

The novel esters of this invention have interesting and valuable physiological properties. The compounds are potent serotonin antagonists in vitro tests with the isolated rat uterus and guinea pig ileum preparations. In animals, the compounds act as neurosedatives with a rapid onset of action and are therefore useful in calming domestic or agricultural animals. The activity of the compounds is demonstrated at doses as low as 5-25 mg./kg. when they are administered subcutaneously or intravenously and at doses from about 25-100 mg./kg. orally. The oral LD₅₀ in mice is about 500 to 1000 mg./kg.

In order that the practice of this invention may be more clearly understood, the following non-limiting examples are provided by way of illustration.

EXAMPLE 1

To an ice-cold solution of 5 ml. of concentrated sulfuric acid in 100 ml. of ethylene glycol were added with stirring 7/g. of lysergic acid. The mixture was allowed to warm to room temperature and stirring was continued for about 72 hours, when solution was complete. About 4 volumes of water, to which had been added an excess of concentrated ammonium hydroxide, were added, and the resulting mixture was extracted with ethylene chloride. The combined extracts were dried and concentrated in vacuo. The residue was converted to the maleate salt in a methanol ether solvent mixture. The dried 2-hydroxyethyl 7-methyl-4,6,6a,7,8,9-hexahydroindolo[4,3-fg]quinoline-9-carboxylate maleate melted with decomposition at about 129-136° C.

By employing propane 1,3-diol in the foregoing procedure, the crystalline free base of 3-hydroxypropyl 7-methyl-4,6,6a,7,8,9-hexahydroindolo[4,3-fg]quinoline-9-carboxylate melting at about 128-129° C. is obtained.

EXAMPLE 2

The following compounds were prepared according to the procedure described in Example 1 when dihydrolysergic acid was reacted with the indicated polyhydric alcohol.

2-hydroxyethyl 7-methyl-4,6,6a,7,8,9,10,10a-octahydroindolo-[4,3-fg]quinoline-9-carboxylate maleate, M.P. (dec.) about 161-163° C., prepared with ethylene glycol.

3-hydroxypropyl 7-methyl-4,6,6a,7,8,9,10,10a-octahydroindolo-[4,3-fg]quinoline-9-carboxylate, M.P. (dec.) about 155-156° C., prepared with propane-1,3-diol.

2-hydroxypropyl 7-methyl-4,6,6a,7,8,9,10,10a-octahydroindolo-[4,3-fg]quinoline-9-carboxylate, M.P. (dec.) about 178-182° C., prepared with propane-1,2-diol.

2,3-dihydroxypropyl 7-methyl-4,6,6a,7,8,9,10,10a-octahydroindolo-[4,3-fg]quinoline-9-carboxylate, M.P. (dec.) about 115-117° C., prepared with glycerol.

4-hydroxybutyl 7-methyl-4,6,6a,7,8,9,10,10a-octahydroindolo-[4,3-fg]quinoline-9-carboxylate, M.P. (dec.) about 163-165° C., prepared with butane-1,4-diol.

3-hydroxybutyl 7-methyl-4,6,6a,7,8,9,10,10a-octahydroindolo-[4,3-fg]quinoline-9-carboxylate, M.P. (dec.) about 141-144° C., prepared with butane-1,3-diol.

5-hydroxypentyl 7-methyl-4,6,6a,7,8,9,10,10a-

octahydroindolo-[4,3-fg]quinoline-9-carboxylate, M.P. (dec.) about 156-158° C., prepared with pentane-1,5-diol.

EXAMPLE 3

5-When 4-methyllysergic acid was reacted with ethylene glycol in the procedure described in Example 1, 2-hydroxyethyl 4,7-dimethyl-4,6,6a,7,8,9-hexahydroindolo[4,3-fg]quinoline-9-carboxylate maleate was obtained melting at about 80-85° C. (dec.)

10-In an analogous manner, the compounds listed below were prepared from the indicated 4-substituted lysergic acid and the indicated polyhydric alcohol.

2-hydroxypropyl 4,7-dimethyl-4,6,6a,7,8,9-hexahydroindolo[4,3-fg]quinoline-9-carboxylate maleate, M.P. (dec.) about 79-82° C., prepared from propane-1,2-diol and 4-methyllysergic acid.

3-hydroxypropyl 4,7-dimethyl-4,6,6a,7,8,9-hexahydroindolo[4,3-fg]quinoline-9-carboxylate maleate, M.P. (dec.) about 85-90° C., prepared from propane-1,3-diol and 4-methyllysergic acid.

2-hydroxypropyl 4-isopropyl-7-methyl-4,6,6a,7,8,9-hexahydroindolo[4,3-fg]quinoline-9-carboxylate maleate, M.P. (dec.) about 128-134° C., prepared from propane-1,2-diol and 4-isopropyllysergic acid.

3-hydroxypropyl-4-isopropyl-7-methyl-4,6,6a,7,8,9-hexahydroindolo[4,3-fg]quinoline-9-carboxylate maleate, M.P. (dec.) about 100-105° C., prepared from propane-1,3-diol and 4-isopropyllysergic acid.

2-hydroxy-1-methylpropyl 4-isopropyl-7-methyl-4,6,6a,7,8,9-hexahydroindolo[4,3-fg]quinoline-9-carboxylate, M.P. (dec.) about 146-148° C., prepared from butane-2,3-diol and 4-isopropyllysergic acid.

2-hydroxyethyl 4-benzyl-7-methyl-4,6,6a,7,8,9-hexahydroindolo-[4,3-fg]quinoline-9-carboxylate maleate, M.P. (dec.) about 100-105° C., prepared from ethylene glycol and 4-benzyllysergic acid.

EXAMPLE 4

40-When 4-methyldihydrolysergic acid was reacted with ethylene glycol according to the procedure described in Example 1 there was obtained 2-hydroxyethyl 4,7-dimethyl-4,6,6a,7,8,9,10,10a-octahydroindolo[4,3-fg]quinoline-9-carboxylate melting at about 153-155° C.

45-In an analogous manner, the compounds listed below were prepared from the indicated 4-substituted dihydrolysergic acid and the indicated polyhydric alcohol.

3-hydroxypropyl 4,7-dimethyl-4,6,6a,7,8,9,10,10a-octahydroindolo[4,3-fg]quinoline-9-carboxylate maleate, M.P. (dec.) about 168-173° C., prepared from propane-1,3-diol and 4-methyldihydrolysergic acid.

2-hydroxypropyl 4,7-dimethyl-4,6,6a,7,8,9,10,10a-octahydroindolo[4,3-fg]quinoline-9-carboxylate maleate, M.P. (dec.) about 173-176° C., prepared from propane-1,2-diol and 4-methyldihydrolysergic acid.

55-2,3-dihydroxypropyl 4,7-dimethyl-4,6,6a,7,8,9,10,10a-octahydroindolo[4,3-fg]quinoline-9-carboxylate maleate, M.P. (dec.) about 169-174° C., prepared from glycerol and 4-methyldihydrolysergic acid.

4-hydroxybutyl 4,7-dimethyl-4,6,6a,7,8,9,10,10a-octahydroindolo[4,3-fg]quinoline-9-carboxylate, M.P. (dec.) about 131-133° C., prepared from butane-1,4-diol and 4-methyldihydrolysergic acid.

3-hydroxybutyl 4,7-dimethyl-4,6,6a,7,8,9,10,10a-octahydroindolo[4,3-fg]quinoline-9-carboxylate maleate, M.P. (dec.) about 119-121° C., prepared from butane-1,3-diol and 4-methyldihydrolysergic acid.

2-hydroxypropyl 4-ethyl-7-methyl-4,6,6a,7,8,9,10,10a-octahydroindolo[4,3-fg]quinoline-9-carboxylate maleate, M.P. (dec.) about 180-182° C., prepared from propane-1,2-diol and 4-ethyldihydrolysergic acid.

3-dihydroxypropyl 4-ethyl-7-methyl-4,6,6a,7,8,9,10,10a-octahydroindolo[4,3-fg]quinoline-9-carboxylate, M.P. (dec.) about 128-129° C., prepared from glycerol and 4-ethyldihydrolysergic acid.

2 - hydroxypropyl 4 - n - propyl - 7 - methyl - 4,6,6a, 7,8,9,10,10a - octahydroindolo[4,3 - fg]quinoline - 9 - carboxylate maleate, M.P. (dec.) about 106-108° C., prepared from propane-1,2-diol and 4-n-propyldihydrolysergic acid.

2,3 - dihydroxypropyl 4 - n - propyl - 7 - methyl - 4,6, 6a, 7,8,9,10,10a - octahydroindolo[4,3 - fg]quinoline - 9 - carboxylate, M.P. (dec.) about 138-140° C., prepared from glycerol and 4-n-propyldihydrolysergic acid.

2 - hydroxyethyl 4 - isopropyl - 7 - methyl - 4,6,6a, 7,8,9,10,10a - octahydroindolo[4,3 - fg]quinoline - 9 - carboxylate maleate, M.P. (dec.) about 135-140° C., prepared from ethylene glycol and 4-isopropyldihydrolysergic acid.

3 - hydroxypropyl 4 - isopropyl - 7 - methyl - 4,6,6a, 7,8,9,10,10a - octahydroindolo[4,3 - fg]quinoline - 9 - carboxylate, M.P. (dec.) about 135-137° C., prepared from propane-1,3-diol and 4 - isopropyldihydrolysergic acid.

2 - hydroxypropyl 4 - isopropyl - 7 - methyl - 4,6,6a, 7,8,9,10,10a - octahydroindolo[4,3 - fg]quinoline - 9 - carboxylate maleate, M.P. (dec.) about 121-124° C. prepared from propane-1,2-diol and 4-isopropyldihydrolysergic acid.

2,3 - dihydroxypropyl 4 - isopropyl - 7 - methyl - 4,6, 6a, 7,8,9,10,10a - octahydroindolo[4,3 - fg]quinoline - 9 - carboxylate, M.P. (dec.) about 165-167° C., prepared from glycerol and 4-isopropyldihydrolysergic acid.

4 - hydroxybutyl 4 - isopropyl - 7 - methyl - 4,6,6a, 7,8,9,10,10a - octahydroindolo[4,3 - fg]quinoline - 9 - carboxylate, M.P. (dec.) about 150-155° C., prepared from butane-1,4-diol and 4-isopropyldihydrolysergic acid.

3 - hydroxybutyl 4 - isopropyl - 7 - methyl - 4,6,6a, 7,8,9,10,10a - octahydroindolo[4,3 - fg]quinoline - 9 - carboxylate, M.P. (dec.) about 116-120° C., prepared from butane-1,3-diol and 4-isopropyldihydrolysergic acid.

2 - hydroxy - 1 - methylpropyl 4 - isopropyl - 7 - methyl-4,6,6a,7,8,9,10,10a - octahydroindolo[4,3 - fg]quinoline - 9 - carboxylate, M.P. (dec.) about 166-168° C., prepared from butane-2,3-diol and 4-isopropyldihydrolysergic acid.

2,4 - dihydroxybutyl 4 - isopropyl - 7 - methyl - 4,6,6a, 7,8,9,10,10a - octahydroindolo[4,3 - fg]quinoline-9-carboxylate, M.P. (dec.) about 166-170° C., prepared from butane-1,2,4-triol and 4-isopropyldihydrolysergic acid.

5 - hydroxypropyl 4 - isopropyl - 7 - methyl-4,6,6a,7,8,9, 10,10a - octahydroindolo[4,3 - fg]quinoline - 9 - carboxylate, M.P. (dec.) about 122-124° C., prepared from pentane-1,5-diol and 4-isopropyldihydrolysergic acid.

2,3 - dihydroxypropyl 4 - allyl - 7 - methyl - 4,6,6a,7,8, 9,10,10a - octahydroindolo[4,3 - fg]quinoline - 9 - carboxylate, M.P. (dec.) about 124-130° C., prepared from glycerol and 4-allyldihydrolysergic acid.

2 - hydroxyethyl 4 - allyl - 7 - methyl - 4,6,6a,7,8,9,10, 10a - octahydroindolo[4,3 - fg]quinoline - 9 - carboxylate, M.P. (dec.) about 55-60° C., prepared from ethylene glycol and 4-allyldihydrolysergic acid.

3 - hydroxypropyl 4 - benzyl - 7 - methyl - 4,6,6a,7,8,9, 10,10a - octahydroindolo[4,3 - fg]quinoline - 9 - carboxylate maleate, M.P. (dec.) about 118-120° C., prepared from propane-1,3-diol and 4-benzylidihydrolysergic acid.

2 - hydroxyethyl 4 - benzyl - 7 - methyl - 4,6,6a,7,8,9, 10,10a - octahydroindolo[4,3 - fg]quinoline - 9 - carboxylate maleate, M.P. (dec.) about 156-158° C., prepared from ethylene glycol and 4-benzylidihydrolysergic acid.

2,3 - dihydroxypropyl 4 - benzyl - 7 - methyl - 4,6,6a, 7,8,9,10,10a-octahydroindolo[4,3 - fg]quinoline - 9 - carboxylate, M.P. (dec.) 113-115° C., prepared from glycerol and 4-benzylidihydrolysergic acid.

EXAMPLE 5

A solution containing 50 g. of 4-isopropyldihydrolysergic acid and 50 g. of p-toluenesulfonic acid dissolved in 500 ml. of butane-2,3-diol was warmed at a temperature of about 50° C. for 24 hours. The reaction product mixture was diluted with four volume of water containing in

solution an excess of ammonium hydroxide and the resulting mixture extracted with ethylene chloride. The extract was washed with water, dried and concentrated by evaporation in vacuo to yield a light tan residue. The residue was crystallized from aqueous acetonitrile to yield 41 g. of 2-hydroxy-1-methylpropyl 4-isopropyl-7-methyl-4,6,6a,7,8,9,10,10a - octahydroindolo[4,3 - fg]quinoline-9-carboxylate melting at about 168-170° C.

EXAMPLE 6

10 The following compounds are prepared according to the procedure of Example 6 when the indicated lysergic or dihydrolysergic acid is reacted with the specified polyhydroalcohol.

15 3-hydroxycyclopentyl 4,7-dimethyl-4,6,6a,7,8,9-hexahydro[4,3-fg]quinoline-9-carboxylate is prepared from 4-methyllysergic acid and cyclopentane-1,3-diol.

20 8-hydroxyoctyl 4,7-dimethyl-4,6,6a,7,8,9-hexahydro[4,3-fg]quinoline-9-carboxylate is prepared from 4-methyllysergic acid and octane-1,8-diol.

25 4-hydroxycyclohexyl 7-methyl-4,6,6a,7,8,9,10,10a-octahydroindolo[4,3-fg]quinoline-9-carboxylate is prepared from dihydrolysergic acid and cyclohexane-1,4-diol.

30 2-hydroxycycloheptyl 4-isopropyl-7-methyl-4,6,6a,7,8,9, 10,10a-octahydroindolo[4,3-fg]quinoline-9-carboxylate is prepared from 4-isopropyldihydrolysergic acid and cycloheptane-1,2-diol.

35 5-hydroxycyclooctyl 4-isopropyl-7-methyl-4,6,6a,7,8,9, 10,10a-octahydroindolo[4,3-fg]quinoline-9-carboxylate is prepared from 4-methyldihydrolysergic acid and 3-(n-propyl)cyclooctane-1,5-diol.

40 2-hydroxy-4-methylcycloheptyl 4,7-dimethyl-4,6,6a,7,8, 9-hexahydroindolo[4,3-fg]quinoline-9-carboxylate is prepared from 4-methyllysergic acid and 4-methylcycloheptane-1,2-diol.

45 I claim:

1. A compound selected from the group consisting of compounds of the formula

60 and the salts thereof with pharmaceutically acceptable acids, wherein R¹ is hydrogen, C₁-C₃ lower alkyl, allyl or benzyl and R² is C₂-C₈ monohydroxyalkyl, C₂-C₈ dihydroxyalkyl or C₅-C₁₁ monohydroxycycloalkyl having from 5 to 8 ring carbon atoms.

65 2. The compound of claim 1 of the formula

70 wherein R¹ and R² are defined as in claim 1.

3. The compound of claim 2, said compound being 2-hydroxy-1-methylpropyl 4-isopropyl-7-methyl-4,6,6a,7,8,9,10,10a-octahydroindolo[4,3-fg]quinoline-9-carboxylate.

4. The compound of claim 2, said compound being 2-hydroxypropyl 4,7-dimethyl-4,6,6a,7,8,9,10,10a-octahydroindolo[4,3-fg]quinoline-9-carboxylate.

5. The compound of claim 2, said compound being 2-hydroxypropyl 4-isopropyl-7-methyl-4,6,6a,7,8,9,10,10a-octahydroindolo[4,3-fg]quinoline-9-carboxylate.

6. The compound of claim 2, said compound being 2-hydroxyethyl 4-allyl-7-methyl-4,6,6a,7,8,9,10,10a-octahydroindolo[4,3-fg]quinoline-9-carboxylate.

7. The compound of claim 2, said compound being 2,3-dihydroxypropyl 4-ethyl-7-methyl-4,6,6a,7,8,9,10,10a-octahydroindolo[4,3-fg]quinoline-9-carboxylate.

8. The compound of claim 1 of the formula

wherein R¹ and R² are defined as in claim 1.

9. The compound of claim 8, said compound being 2-hydroxy-1-methylpropyl 4-isopropyl-7-methyl-4,6,6a,7,8,9-hexahydroindolo[4,3-fg]quinoline-9-carboxylate.

10. The compound of claim 8, said compound being 2-hydroxypropyl 4-isopropyl-7-methyl-4,6,6a,7,8,9-hexahydroindolo[4,3-fg]quinoline-9-carboxylate.

11. The compound of claim 8, said compound being 2-hydroxyethyl 4,7-dimethyl-4,6,6a,7,8,9-hexahydroindolo[4,3-fg]quinoline-9-carboxylate.

12. The compound of claim 8, said compound being 2-hydroxyethyl 4-benzyl-7-methyl-4,6,6a,7,8,9-hexahydroindolo[4,3-fg]quinoline-9-carboxylate.

13. The compound of claim 8, said compound being 2-hydroxypropyl 4,7-dimethyl-4,6,6a,7,8,9-hexahydroindolo[4,3-fg]quinoline-9-carboxylate.
